UNITED STATES PATENT OFFICE.

OSCAR F. ARMSTRONG, OF HAVERHILL, MASSACHUSETTS, ASSIGNOR TO ERNEST D. HASELTINE CO., OF HAVERHILL, MASSACHUSETTS, A CORPORATION OF MASSACHUSETTS.

SOLE-GROOVING MACHINE.

1,417,018.

Specification of Letters Patent. Patented May 23, 1922.

Application filed April 18, 1921. Serial No. 462,225.

To all whom it may concern:

Be it known that I, OSCAR F. ARMSTRONG, a citizen of the United States, and a resident of Haverhill, in the county of Essex, State 5 of Massachusetts, have invented an Improvement in Sole-Grooving Machines, of which the following is a specification.

This invention relates to that class of machines which are designed to operate on 10 inner-soles used in the manufacture of welt and McKay-sewed shoes, for the purpose of making them more flexible.

Prior to my invention the machines of 15 this type, which have been most generally used, are arranged to slash the sole from one side edge to the other by a series of parallel cuts in the flesh side. This operation does not, however, give the desired degree of flexibility and I have discovered 20 that, in order to secure such desired degree of flexibility, a portion of the leather must be actually removed from the flesh side, but that this must not be done in a manner to effect the serviceability of the sole, or by, 25 in any way, weakening the edge portion of the sole in which the upper attaching stitches must be formed. I have further ascertained that the desired result will be secured by forming a series of narrow, suitably spaced, 30 transverse, parallel grooves, in the ball portion of the sole, said grooves being formed to terminate at a suitable distance from its side edges.

The primary object of my invention is to 35 provide a machine for forming such grooves, which will perform the operation rapidly and effectively and at small expense, without danger of injury to the sole or impairment of its serviceability.

40 I accomplish these objects in the manner hereinafter described and illustrated in the accompanying drawings, in which an embodiment of my invention is shown and in which:—

45 Fig. 1 is a side elevation of a machine embodying my invention.

Fig. 2 is a plan view and

Fig. 3 is a front elevation thereof.

Fig. 4 is a vertical sectional view at the 50 line $x-x$ of Fig. 1.

Fig. 5 is a sectional view at the line $y-y$ of Fig. 3.

Fig. 6 is a detail plan view of the sole-supporting plate.

Fig. 7 is a detail sectional view of one of 55 the cutters.

Fig. 8 is an enlarged detail view of some of the cutter teeth.

Figs. 9 and 10 are plan and sectional views of a sole which has been operated on by the 60 machine.

As shown in the drawing the base plate 1 of the machine has a pair of bearing brackets 2 mounted thereon, in which a shaft 3 is journaled, said shaft being adapted to 65 be rotated continuously. Three pulleys 4, 5 and 6 are mounted on said shaft, the pulleys 4 and 6 respectively adjacent said bearings and the pulley 5 midway therebetween. Four upright guide posts 7 are 70 mounted in the base 1 and a guard plate 8 is fixed on the upper ends thereof in a horizontal position, or parallel to the base, said plate being secured thereon by any suitable means, as by clamping it against shoulders 75 on the posts by nuts 9 threaded thereon. A series slots 10 are formed in the plate 8, which extend from front to rear. A rectangular shaped guide plate 11 is mounted to slide vertically on said posts 7 and a rod 12 is connected to the under side thereof and 80 extends downward through the base and through a stirrup bracket 13, attached to the under side of the base, and in which said rod is adapted to reciprocate, vertically. 85 A spring 14 is arranged between the bracket 13 and a collar 15, which is secured on the rod 12 and is normally held against the under side of the base by said spring. A treadle 16 is connected to the lower end of 90 the rod 12, and arranged so that, when it is pressed, the rod will be pulled downward, against the action of spring 14, causing the plate 11 to be moved down therewith. A sole-supporting plate 18 is mounted to slide 95 forwardly and rearwardly on the plate 11, said plate 18 having guiding ribs 19, on its under side, arranged to engage the side edges and under side of the plate 11, as shown in Fig. 4. A projecting lug 20 is formed on 100 the rear edges of the plate 18 and a link 21 is connected thereto, at one end, by a pivot 22, and at the opposite end said link is pivoted to an arm 23 on a shaft 24, journaled

in brackets 25 on the base 1. A hand lever 26 is secured on said shaft 24 and extended beneath the base beyond the front end thereof, and a spring 27 is connected to said lever and normally acts to hold the lever and parts connected thereto in the full line position of Fig. 1.

By this arrangement, when the lever 26 is pushed downward the plate 18 will be pushed forward on plate 11 to the dotted line position of Fig. 1. Adjustable stop screws 28 and 29 are mounted in lugs on the plate 11, at the front and rear ends thereof, respectively, to limit the forward and rearward movements of the plate 18, the spring 27 normally acting to hold the plate against the screw 29.

A curved U-shaped bracket 30 is mounted on the upper side of the plate 8, at the rear thereof, and a shaft 31 is journaled in the arms of said bracket. A gang of equally spaced, rotary cutters 32 are mounted on the shaft 31, four of said cutters being preferably provided, and a pulley 33 is mounted on the shaft 31 at the middle thereof, and is adapted to be driven from the middle pulley 5, by a belt 34. A pair of bearing brackets 35 and 36 are mounted on the plate 8 at opposite sides thereof and shafts 37 and 38, respectively, are journaled therein. Pulleys 39 and 40, are mounted on the shafts 37 and 38, at their opposite ends, and are driven by belts 41 and 42 from the pulleys 4 and 6, respectively. A rotary cutter 43 is mounted on the opposite end of the shaft 37 from the pulley 39, at a distance from the next adjacent cutter 32 approximately equal to the spaces between the cutters 32, and a rotary cutter 44 is mounted on the adjacent end of shaft 38, in similar relation to the cutters 32. In construction the cutters 32, 32 and 44 are all somewhat similar to ordinary circular saws, and have hook-shaped teeth, as shown in Fig. 8, which are adapted to make a cut of a width corresponding to their thickness. The diameters of the intermediate cutters 32 are the same, and substantially greater than the diameters of either cutter 43 or 44, and the diameter of the cutter 43 is substantially less than that of the cutter 44. The cutters operate in the slots 10 of the guard plate 8 and each cutter extends the same distance beneath the under surface of the plate, as shown in Fig. 4. The collar 15 is so located that it will prevent contact of the plate 18 with the cutter teeth when raised to its fullest extent by the spring 14.

The axes of the shafts 31, 37 and 38 all lie in the same vertical plane and the relative sizes of the pulleys 39, 33 and 40 are preferably such that the peripheral speed of each cutter will be approximately the same. The cutters are driven in the direction of the arrow in Figs. 1 and 8, so that the

teeth move rearwardly beneath their respective shafts.

A toe gage 45 is mounted on the plate 18, at the left hand end thereof, said gage being mounted for adjustment longitudinally of the plate between guide ways 46 thereon and a pointer 47 is preferably connected to said gage and suitable graduations are provided so that the gage may be quickly set according to the length of sole 75 to be operated on. A side gage 48 is also mounted on the plate 18 at the rear thereof in position to engage the edge of the shank or heel portion of a sole supported on the plate with its toe end engaged with the toe 80 gate 45.

In practice the soles will be sorted, so that all lefts, or all rights, of one size may be operated on without changing the adjustment of the machine. When the gages have 85 been properly adjusted for one lot of soles, the operator depresses the treadle 16, drawing down the plate 18, so that the sole may be placed in position thereon, in contact with the gages 45 and 48, as indicated in Figs. 2 90 and 6. The treadle will then be released permitting the spring 14 to lift the sole up into engagement with the cutters and press its upper side against the under side of the plate 8, so that the cutters will cut into the 95 sole to a depth equal to the extent which they dip below the surface of the plate 8. In this connection it is to be noted that the sole is pressed against the plate 8 by the spring 14, and not by the action of the operator in pressing on the treadle. This is important, as the soles will always be pressed against the plate by the same force and the depth of the cut cannot be increased by pressing the sole against the plate with unnecessary force. The position of the plate 8 with relation of the saws thus always determines the depth of the grooves which are cut, so that, to increase the depth thereof, the plate 8 would be adjusted upward on the 100 posts 7, and to decrease it the plate would be adjusted downward, thereon. As soon as the operator releases the treadle, so that the sole is pressed against the plate 8, he depresses the hand lever 26, causing the sole 115 support to be moved forward to the dotted line position of Fig. 1. The sole gages are so set that when the sole is first moved into contact with the cutters the grooves cut thereby will extend from points at distance 120 from the front edge of the sole, as it lies on the support, somewhat greater than the width of the sole-edge portion which receives the upper attaching stitcher, so that, as the sole support is moved forward, by the hand lever, the grooves in the sole will be extended towards its opposite edge. The adjustment of the stop screw 28 will be such that, when further forward movement of the sole support is prevented by said screw, the 130

grooves will be cut to within the same proximity of the sole edge at the rear as at the front. A series of transverse grooves will thus be formed in the sole fore-part, as illustrated in Figs. 9 and 10. When the lever 5 26 is released, the sole-support 18 will be moved back to its initial position and the treadle will be depressed to permit the removal of the sole and the insertion of another sole. 10

As the toe gage is not designed to be adjusted laterally, the position as well as the length of the grooves which will be formed in the sole, will be determined by the adjustment of the stop screws 28 and 29, except that the position will be also affected by the adjustment of the edge gage 48, the position of which determines the angular position of the grooves with relation to the sole edge and to some extent the points at which the grooves terminate. 20

It will be noted that, as all the cutters dip below the plate 8 to the same extent, the length of groove cut by each cutter will depend on the cutter's diameter. For this reason the four intermediate cutters of greatest diameter are arranged to operate on the widest portion of the sole, and, as the sole tapers rapidly from the ball to the shank, the cutter 43, of least diameter, is arranged to operate at this point, and, as the sole tapers less rapidly in front of the ball, the cutter 44, which operates nearest the toe, is made of an intermediate diameter. 30

It will be understood, however, that the invention is not limited to the number, size or location of the cutters, as these will be varied somewhat according to the size of soles to be operated, the present embodiment shown being especially designed for use in connection with soles for women's shoes, although it may be used in connection with soles for men's shoes also. 35

I claim:

45 1. A sole-grooving machine comprising a gang of rotary grooving cutters, a guard plate through which said cutters extend a distance corresponding to the depth of groove to be cut, a sole-support, spring actuated means for moving said support perpendicularly of its face, to press a sole thereon against said plate and in position to be engaged by said cutters, manually operated means for withdrawing said support from said plate, and manually operated means for moving said support transversely. 50

55 2. A sole-grooving machine comprising a series of rotary grooving cutters arranged to rotate about axes which lie in approximately the same vertical plane and spaced apart at approximately uniform distances, a slotted guard plate in which said cutters are arranged to operate, the diameter of the cutter at one the end of said series being substantially less than that of the other 60

cutters and all of said cutters being arranged to project to a uniform extent beyond said plate, a sole support and means to move the same to press a sole against said plate in position to be engaged by said cutters. 70

3. A sole-grooving machine comprising a series of rotary grooving cutters arranged to rotate about axes which lie in approximately the same vertical plane and spaced apart at approximately uniform distances, a slotted guard plate in which said cutters are arranged to operate, the diameter of the cutters at each end of said series being substantially less than that of the intermediate cutters and all of said cutters being arranged to project to a uniform extent beyond said plate, a sole support and means to move the same to press a sole against said plate in position to be engaged by said cutters. 75

4. A sole-grooving machine comprising a series of rotary grooving cutters, a shaft on which said cutters are mounted, a shaft at each end of said series of cutters each having a rotary cutter thereon of smaller diameter than that of said series of cutters and arranged to rotate in proximity to the end cutters, respectively, of said series and in parallel thereto, a slotted guard plate in 90 the slots of which said cutters are arranged to rotate and to extend to approximately the same extent beyond the opposite side of the plate from that at which they are mounted, a sole-support and means to move the same to press a sole against said plate, and separate means for driving each cutter shaft. 95

5. A sole-grooving machine comprising a horizontally fixed guard plate having a parallel series of slots extending therethrough, a series of rotary cutters mounted above said plate and arranged in said slots to extend below the under side of said plate, a vertically movable guide having a sole-support mounted to slide horizontally thereon beneath said plate, to hold a sole against said plate in position to be engaged by said cutters, a spring arranged to lift said guide and sole-support, a stop arranged to limit the upward movement of said support at a point at which its sole-supporting face is in close proximity to, and out of contact with said cutters, and manually operated means for moving said support downwardly and horizontally. 110

6. A sole-grooving machine comprising a horizontally fixed guard plate having a parallel series of slots extending therethrough, a series of rotary cutters mounted above said plate and arranged in said slots to extend below the under side of said plate, a vertically movable guide having a sole-support mounted to slide horizontally thereon beneath said plate to hold a 115 120 125 130

sole against said plate in position to be engaged by said cutters, a spring arranged to lift said guide to press a sole on said support against the under side of said plate, 5 a spring arranged to move said sole support horizontally to an initial position, and independent means under the control of the

operator for moving said guide downwardly and for moving said support horizontally against the action of said springs.

In testimony whereof, I have signed my name to this specification.

OSCAR F. ARMSTRONG.
